CLAIM

The ornamental design for a spacer for a vehicle suspension, as shown and described.

DESCRIPTION

FIG. 1 is a perspective view of a first embodiment of the spacer for a vehicle suspension;

FIG. 2 is another perspective view of the first embodiment;

FIG. 3 is a left side elevational view of the first embodiment as shown in FIG. 1;

FIG. 4 is a front elevational view of the first embodiment as shown in FIG. 1;

FIG. 5 is a right side elevational view of the first embodiment as shown in FIG. 1;

FIG. 6 is a rear elevational view of the first embodiment as shown in FIG. 1;

(Continued)

FIG. 7 is a top plan view of the first embodiment as shown in FIG. 1; and,
FIG. 8 is a bottom plan view of the first embodiment as shown in FIG. 1.
The broken lines shown in the drawings are for illustrative purposes only and form no part of the claimed design.
